DRAFT AND BUFFER GEARING

Glenn E. Edmunds, Columbus, Ohio, assignor to
The Bonney-Floyd Company, Columbus, Ohio,
a corporation of Ohio

Application April 12, 1934, Serial No. 720,323

13 Claims. (Cl. 213—9)

The present invention relates to draft and buffer gearing utilizing friction means for resisting movements, under draft and buffing forces, of movable draft and buffer elements.

5 According to the invention, in its preferred embodiment, cooperating friction surfaces enter into action both under draft and buffing forces and the friction surfaces in each instance are engaged through common yieldable means, the latter being 10 preferably in the form of a compression spring or springs. The buffing means may take the form of a plurality of separate buffing heads or of a single bumper, and, while the invention is of general application, it is particularly well adapted 15 for use in mine cars and in mine and industrial locomotives or the like.

In order that the underlying principles and the scope of the invention may be readily understood, I have shown several illustrative embodiments in the accompanying drawings. In these 20 embodiments, friction transmission means come into action both under draft and buffing forces. The invention is not limited in this respect, however, since the friction buffing means may be used 25 in conjunction with fixed or positive draft means or the friction draft means may be used in conjunction with a solid bumper. That is to say, the invention embraces friction draft means per se and friction buffing means per se.

30 In the drawings:

Figure 1 is a plan view, partly in section of one practical embodiment of the invention;

Figure 2 is an elevation, partly in section, of the embodiment of Figure 1;

35 Figure 3 is a section substantially one line 3—3 of Figure 2;

Figure 4 is a plan view, partly in section, of a modified form of the invention;

Figure 5 is a plan view partly in section of an 40 other embodiment of the invention;

Figure 6 is a section substantially on the line 6—6 of Figure 5;

Figure 7 is a plan view, partly in section, of still 45 another embodiment of the invention;

45 Figure 8 is a section substantially on line 8—8 of Figure 7;

Figure 9 is a section substantially on line 9—9 of Figure 7;

50 Figure 10 is a plan view of a still further embodiment of the invention, partly in section;

Figure 11 is a section substantially on line 11—11 of Figure 10;

55 Figure 12 is a plan view, partly in section, of another form which the invention may take; and

Figure 13 is an elevation, partly in section, of the embodiment of Figure 12.

Referring first to Figures 1 to 3, reference numeral 20 designates generally a bracket or housing, preferably an integral casting, comprising top and bottom webs 21 and 22 connected by end walls 23 and 24 which are rearwardly prolonged into arms 25 and 26 adapted to be secured to longitudinal sill members, not shown, of a car. The top and bottom webs and side walls are connected by a rear wall 27 which, as here shown, is of angular form to provide a pocket 28 having an apex on the central longitudinal line of the bracket. Centrally, web 21 is interrupted by a recess 29 and therebelow the lower web 22 has a 15 downwardly offset portion 30. A draft member in the form of a bar 31 is of substantially the same form as the similar bar shown in my Patent No. 2,060,052, granted November 10, 1936, and has similarly connected thereto a draft hook or other 20 suitable coupling element 32. The end portions of bar 31 have flat vertical walls as at 33, each being provided with a vertically extending lug or rib as at 34, Figures 1 and 3.

As shown in Figures 1 to 3, the use of a pair 25 of separate buffer heads 35 and 36 is contemplated, although the invention is by no means limited in this respect since it is readily adaptable to the requirements of a single buffing means in the form of a single bumper extending from side 30 to side of the bracket. Heads 35 and 36 are identical in form and mounting so that a description of one will suffice.

Referring particularly to head 35, the same is 35 of substantially box-like form, rectangular in cross section, and comprises top and bottom walls 37 and 38 and side walls 39 and 40, the top and bottom walls being so spaced as to be slidable between bracket webs 21 and 22. Preferably, but not necessarily, the head is an integral casting 40 and comprises also a forward buffing face 41 which is laterally rounded off in each direction.

The top and bottom walls 37 and 38 are connected by means of vertical webs 42 and 43 which rearwardly and, at least throughout their major 45 portions, have forwardly convergent opposed friction faces, the forward ends of these webs merging into the front wall 41. The top and bottom walls 37 and 38 are provided with registering openings 44, 45 and 46, 47, these openings being 50 in the form of slots extending in the fore and aft direction and forwardly enlarged as shown in Figure 1, these slots lying between wall 39 and web 42 and wall 40 and web 43, respectively. Bracket webs 21 and 22 are provided with aligned 55

apertures and pins 48 and 49 are passed through these apertures and the registering slots in head 35. Thus, due to the provision of the slots in the head, the latter has the capability of limited movement toward and away from the bracket in the fore and aft direction and it may also pivot about either one of pins 48 and 49 due to the clearance provided by the enlarged forward ends of the slots. The head is sufficiently inwardly spaced from wall 23 so as not to interfere therewith.

A compressible wedge comprising shoes 50 and 51 has inclined friction faces engaging the opposed faces of webs 42 and 43. The wedge shoes or portions are provided with opposed centering bosses 52, 53 and 54, 55, which position compression springs 56 and 57, which are interposed between the shoes, to force the latter against the cooperating friction faces of the head. The base portion of the wedge bears against the forward face 33 of bar 31 and the lug or rib 34 extends between the wedge portions. A plate 58 bridges the forward ends of the wedge portions and provides a seat for the rear end of a compression spring 59 whose forward end abuts the rear surface of wall 41 and is centered thereon by means of a boss 60. It will be understood that head 36 has exactly the same provisions as those just described with reference to head 35.

30 The assembly of the parts described is readily accomplished. The draft member 31 is inserted to positions and the hook 32 connected therewith in the manner described in the application above mentioned. The compressible wedge, together with plate 58 and spring 59, are assembled in head 35, whereupon the latter is inserted to position and pins 48 and 49 are dropped in place and secured in any suitable manner.

Upon application of draft to hook 32, bar 31 may be moved forwardly, or outwardly, relative to bracket 20. This movement takes place against the force of spring 59, the frictional resistance between the wedge and webs 42 and 43 being of a magnitude dependent upon the strength of springs 56 and 57. The strength of these springs may be chosen as required, and under some conditions only one of these springs may be necessary to secure the desired results.

When draft tension is relieved or released, spring 59 acts to return the drawbar into abutment with wall 27 and to hold the drawbar and buffer head in maximum spaced relation as shown in Figure 1. It will be understood that, under buffing forces, rearward movements of the heads relative to the housing are similarly resisted by the springs as at 59 and the friction faces, return of the heads being effected by the said springs.

As here shown, the friction faces of the wedge are related at a very acute angle so that return means such as spring 59 is required. Under some circumstances, as when the friction faces of the wedge are sufficiently obtusely related, spring 59 may be dispensed with, inasmuch as the action of springs 56 and 57 will then suffice for all purposes. The wedge parts are sufficiently spaced at the base of the wedge so as not to interfere with lug 34 which serves, through cooperation with these parts, to maintain the proper relation of the drawbar and wedge. Bar 31 is automatically centered when in abutment with wall 27. Also, plate 58 is of such lateral dimension as not to interfere with webs 42 and 43 and these may be parallel at their forward portions as here shown. The arrangement is extremely flexible so that

under eccentric forces the draft and buffer parts may readily swing relative to each other.

According to Figure 4, the bracket 61 is generally similar to the bracket 20 above described with the principal exception that its rear wall 62, 5 as here shown, is rectilinear. A drawbar 63 has a flat rear surface adapted to abut the front surface of wall 62 and centrally has a pair of forwardly projecting vertically spaced ears as at 64 between which the shank of a draft hook 65 is 10 receivable to be connected thereto by means of a bolt 66 which passes through the top and bottom webs of the bracket in the manner shown in my above mentioned application, although in a somewhat more forward position outside of the 15 adjacent end wall of the car, not shown, due to the absence of the angular, rearwardly extending pocket. The ends of the drawbar 63 are forwardly turned as at 67 and provided with forwardly convergent friction faces as at 68 and 69 which 20 lie opposite a similar, spaced, wedge formation formed on the rear of the front wall 70 of a buffer head 71, this latter wedge formation providing friction faces 72 and 73. The head 71 is connected to the bracket 61 by means of pins 74 and 25 75 in a manner which will be understood from what has gone before.

A pair of opposed wedge blocks 76 and 77 are loosely strung on a rod 78 which, as here shown, has an integral head 79 and a removable head 30 80 at its ends, compression springs 81 and 82 being also strung on rod 78 and respectively abutting with their ends, block 76 and head 79 and block 77 and head 80 so that the faces of the wedge blocks are forced against the faces 68, 72 35 and 69, 73 of the drawbar and buffer head. The blocks 76 and 77 may be considered as providing forward shoe portions yieldingly urged against faces 72 and 73 by means of the compression springs 81 and 82. The wedge blocks are of such 40 height as to be readily receivable between the top and bottom webs of head 71 and are slidably supported on the bottom web. Thus, a floating support is provided so that the blocks readily adjust themselves to conditions. It will be understood that the other buffer head 83 is associated with the bracket 61 and with the drawbar 63 in exactly the same manner as has been described with reference to head 71.

When the drawbar moves away from the 50 bracket under draft, the wedge blocks 76 and 77 are moved apart against the frictional resistance of their faces with faces 68, 69 and 72, 73 and this action is the same under buffing action. Normally the wedge blocks hold the parts in 55 their maximum spaced relation as shown, the springs 81 and 82 being enabled to act as return means in view of the angular relation of the cooperating friction faces. The wedge blocks serve to maintain the centered portion of drawbar 63, although primarily this is maintained by bolt 66, as is also the case in the embodiment first described and as will be understood from the prior application referred to.

In Figures 5 and 6, the bracket 84 is generally 65 the same as the bracket 61, having the same rectilinear rear wall 85. In this case, however, the buffer means is in the form of a single bumper 86 which has slotted top and bottom webs through which are passed pins 87 and 88 to connect the 70 bumper in place between the top and bottom webs 89 and 90 of the bracket. Adjacent each end the bumper is provided with vertical webs as at 91, the opposed faces of these webs being forwardly convergent. The lower wall of the bumper is cut 75

away as at 92 to provide clearance for an up-standing wall 93 integral with the lower web 90 of the bracket. A pair of wedge blocks of which one is shown at 94 is disposed inwardly of wall 93 and have their bases bearing thereagainst adjacent the ends thereof, the opposed faces of the blocks lying in vertical planes which are rearwardly convergent at an angle which is symmetrical relative to the central longitudinal axis of the bumper. The top web 89 of the bracket is centrally interrupted and provided with upwardly offset guide flanges as at 95 in the manner described in the copending application of Edmunds and Cawthon, Serial No. 664,260, filed April 3, 1933. A slide 96 rests on the top wall of bumper 86 and has its marginal portions engaged under the offsets as at 95 so that the slide is guided for movements in the fore and aft direction. The slide is equipped with a tongue 97 thereabove, the two being provided with vertically aligned apertures to receive a coupling pin 98 whose lower end may project into an opening 99 in the bumper top wall so that the pin does not interfere with the relative movements of the bumper and slide. A wedge block 100 has forwardly convergent faces engaging the opposed faces of the blocks as at 94. The wedge block 100 has an upward projection 101 pivoted to the rear portion of slide 96 by means of a bolt 102. The block also has a lower projection 103 projecting through an opening 104 in the bottom wall 90 of the bracket and adapted to bear against the thickened rear edge 105 of this opening. Interposed between bumper web 91 and block 94 is a compressible wedge 106, a compression spring 107 being interposed between the forward end of this wedge and the rear face of the bumper front wall. It will be understood that a similar wedge 106 is provided at the other side of the bracket in engagement with the other wedge block as at 94 and the other bumper web as at 91.

Upon application of draft to the slide 96, wedge block 100 is swung forwardly, as its lower extension 103 rolls on edge 105, and forces the blocks as at 94 apart against the force of the compressible wedges and against the frictional resistance of their engaged portions and of the base faces of the wedge blocks as at 94 with the cooperating surfaces of wall 93, draft being transmitted to the associated car through the latter wall. When draft is relieved, the expansion of the compressible wedges returns the wedge block 100 to normal position. Under buffing action, the bumper moves toward the bracket against the frictional resistance offered by the cooperating faces of the wedges and the bumper webs as at 91, the parts being returned by means of the springs as at 107.

It is believed that the manner of assembly will be perfectly obvious and needs no explanation. These parts are shown as being separate, since ordinarily it will be desirable for ease of manufacture to have the two wedge parts of identical form.

The arrangement shown in Figures 7, 8 and 9 is very similar to that shown in Figures 5 and 6. In this case, however, the rear wall 108 of the bracket 109 is centrally and rearwardly offset as at 110 to provide a pocket 111 whose side walls 112 and 113, Figure 9, are approached at their lower portions. A slide 114 has a pair of ears 115 and 116 depending into the pocket and loosely pivotally connected by a pin 117 with an ear 118 formed at the rear of a wedge block 119. An ear 120 also formed with the wedge block 119 lies between the lower portions of walls 112 and 113 and

is engaged by a pivot pin 121 which also passes through apertures formed in the walls. Wedge blocks, of which one is shown at 122, have their bases arranged against the rear face of a bracket wall 123 and rest on the bottom wall of the bracket. These blocks, as contrasted to the blocks as at 94, Figures 5 and 6, have their opposed faces lying in upwardly, as well as rearwardly, convergent planes, these faces being engaged by complementary faces on the wedge block 119. Upon the application of draft to the slide 114, the block 119 is swung forwardly about pin 121 and exerts a downward and outward action on the wedge blocks as at 122 which is resisted by the compressible wedges of which one is shown at 124. In this case, frictional resistance is developed not only between the blocks as at 122 and the upright bracket wall 123, but also between the blocks and the lower wall of the bracket. Resistance is, of course, also developed between the interengaged blocks themselves.

In assembling this arrangement, the slide is first inserted part way to position, whereupon ear 118 is positioned between ears 115 and 116 and pin 117 inserted. The slide is then moved into its rearward limit position and pin 121 inserted. Pin 117 is held in position by the overlying portions of walls 112 and 113. The blocks, as at 122 are now positioned behind wall 123, the compressible wedges are put in place, the bumper inserted to position, and the retaining pins dropped into place.

The bracket 125 of Figures 10 and 11 has a rearwardly bowed wall 126 against which lies the mating rear surface of a drawbar 127. The drawbar 127 has formed therewith or secured thereto a slide 128 which overlies the central portion of the bumper 129 and is slidably guided in the manner above described. At each end, the drawbar 127 has formed thereon a web as at 130 having a rearwardly and centrally inclined friction face which lies opposite a forwardly and centrally inclined friction face on a web 131 integral with the bumper. The two friction faces are engaged by the faces of a wedge 132 through which is loosely passed a rod 133 which is pivoted at one end to the bumper on a vertical pin 134. A washer 135 is held on the other end of rod 133 between a stop collar 136 and a nut 137 and between the washer and the wedge block 132 are interposed a pair of metal compression springs 138 and 139. The friction faces at the other side of the drawbar and bumper are engaged by a similarly mounted wedge block on a rod pivoted to the bumper at that side. It is believed that the assembly and operation of this form will be entirely evident without explanation. It will be understood that the wedge block under the influence of the springs normally serve to hold the drawbar and bumper in maximum spaced relation and frictionally resist movements of the two toward each other.

In the modification shown in Figures 12 and 13, substantially the same bracket, drawbar, and bumper arrangement is employed as in the arrangement of Figures 10 and 11 and the operation is substantially the same. In this case, however, the friction faces as at 140 and 141 on the drawbar and bumper, respectively, are engaged by a wedge 142 into which freely projects one end of a rod 143 whose other end projects into a similar wedge block at the other side of the bracket. The blocks are urged against the cooperating friction faces by means of compression springs interposed therebetween and between

abutments as at 144 formed on the rod. As here shown, the central portion 145 of the rod 143 is rearwardly offset in order to provide clearance for the lower end of a coupling pin (see Figure 5 6). In order that portion 145 of the rod may be maintained to the rear of the end portions of the 10 rod, as shown in Figure 12, the abutments as at 144 have rectilinear top and bottom edges adjacent the top and bottom webs of the buffer and, 15 through cooperation therewith, prevent the rod from turning. It will be noted that the forward portions of the wedge blocks as at 141 constitute an arrangement which is the same in effect as that shown in a single buffer head in Figure 1, 20 the forward surfaces of the wedge blocks in Figures 12 and 13 corresponding to the outer faces of the shoes 50 and 51, Figure 1.

While various embodiments have been shown, it will be understood that these are susceptible of 20 variation with out departure from the scope of the invention. The shoe elements may be of alloy, heat treated steel, cast iron, etc., and the faces may be ground or machined smooth, or they may be cast smooth. In short, the invention is not 25 limited as to the specific form and material of the parts nor does it exclude the use of expedients commonly practiced in the art.

I claim:

1. Car draft and buffer gearing comprising 30 buffer means and a draft member, said buffer means comprising top and bottom webs and a forward buffering wall, webs extending rearwardly of said forward wall and between said top and bottom webs and providing convergently related 35 friction faces, said rearwardly extending webs being integral with said forward wall and said top and bottom webs, means supporting said buffer means and draft member for movements toward and away from each other, said forward buffering wall projecting beyond said supporting 40 means so as to take buff directly, means connecting the side portions of said buffer means with said supporting means and limiting movement of the buffer means away from the draft member, 45 said connecting means comprising abutment elements directly carried by said supporting means, the buffer means being pivotal about either of said connecting means, friction shoes engaging said convergently related friction faces, and spring 50 means urging said shoes against said friction faces, said supporting means providing means limiting movement of said draft member away from said buffer means, said draft member engaging said friction shoes and the latter normally acting to hold the buffer means and draft member in engagement with their respective 55 limiting means.

2. Car draft and buffer gearing comprising 60 buffer means and a draft member, said buffer means comprising top and bottom webs and a forward buffering wall, vertical webs adjacent the ends of said buffering member extending rearwardly of said forward wall and between said top and bottom webs and providing forwardly convergent 65 opposed friction faces, said rearwardly extending webs being integral with said forward wall and said top and bottom webs, means supporting said buffer means and draft member for movement toward and away from each other, said forward buffering wall projecting beyond said supporting 70 means so as to take buff directly, means connecting the side portions of said buffer means with said supporting means and limiting movement of said buffer means away from said draft member, 75 said connecting means comprising abutment

elements directly carried by said supporting means, the buffer means being pivotal about either of said connecting means, friction shoes engaging said friction faces, compression spring means disposed between said shoes and urging the latter apart and against said friction faces, said supporting means limiting movement of said draft member away from said buffer means, said draft member engaging said friction shoes and the latter normally acting to hold the buffer means and draft member in engagement with their respective limiting means.

3. Car draft and buffer gearing comprising buffer means and a draft member, said buffer means comprising top and bottom webs and a forward buffering wall, vertical webs adjacent the ends of said buffering member extending rearwardly of said forward wall and between said top and bottom webs and providing forwardly convergent opposed friction faces, said rearwardly extending webs being integral with said forward wall and said top and bottom webs, means supporting said buffer means and draft member for movement toward and away from each other, said forward buffering wall projecting beyond said supporting means so as to take buff directly, means connecting the side portions of said buffer means with said supporting means and limiting movement of said buffer means away from said draft member, 30 said connecting means comprising abutment elements directly carried by said supporting means, the buffer means being pivotal about either of said connecting means, friction shoes engaging said friction faces, compression spring means disposed between said shoes and urging the latter apart and against said friction faces, said supporting means limiting movement of said draft member away from said buffer means, said friction shoes being in the form of wedges having their bases in engagement with said draft member, 35 said shoes normally acting to hold the buffer means and draft member in engagement with their respective limiting means.

4. Car draft and buffer gearing comprising buffer means and a draft member, said buffer means being in the form of a bumper designed to extend substantially from side to side of the car at the end of the latter and comprising top and bottom webs and a forward buffering wall, webs extending rearwardly of said forward wall and between said top and bottom webs and providing convergently related friction faces, said rearwardly extending webs being integral with said forward wall and said top and bottom webs, means supporting said buffer means and draft member for movements toward and away from each other, said forward buffering wall projecting beyond said supporting means so as to take buff directly, means connecting the side portions of said buffer means with said supporting means and limiting movement of the buffer means away from the draft member, 50 said connecting means comprising abutment elements directly carried by said supporting means, the buffer means being pivotal about either of said connecting means, friction shoes engaging said convergently related friction faces, and spring means urging said shoes against said friction faces, said supporting means providing means limiting movement of said draft member away from said buffer means, said draft member engaging said friction shoes and the latter normally acting to hold the buffer means and draft member in engagement with their respective 55 limiting means.

5. Car draft and buffer gearing comprising buffer means and a draft member, means supporting said buffer means and draft member for movements toward and away from each other, 5 said buffer means comprising a pair of separate horizontally spaced hollow heads having forward buffing faces and said draft member having end portions extending behind said heads, said forward buffing faces projecting beyond said supporting means so as to take buff directly, each of 10 said heads having at its rear side integral portions providing a pair of faces convergently related with respect to the fore and aft direction, means connecting the side portions of each of 15 said heads with said supporting means and limiting movement of said heads away from the draft member, said connecting means comprising abutment elements directly carried by said supporting means, each of said heads being pivotal about 20 either of said connecting means, said supporting means providing means limiting movement of said draft member away from said buffer means, a pair of friction shoes interposed between each 25 of said heads and the respective end portions of said draft member, each pair of said shoes having faces engaging the friction faces of its associated head, and means yieldingly urging the shoe faces against the said last-named faces. 25
6. Car draft and buffer gearing comprising buffer means and a draft member, means supporting said buffer means and draft member for movements toward and away from each other, said buffer means comprising a pair of separate horizontally spaced hollow heads having forward buffing faces and said draft member having end portions extending behind said heads, said forward buffing faces projecting beyond said supporting means so as to take buff directly, each of 30 said heads having at its rear side integral portions providing a pair of forwardly convergent opposed friction faces, means connecting the side portions of each of said heads with said supporting means and limiting movement of said heads away from the draft member, said connecting means comprising abutment elements directly carried by said supporting means, each of said heads being pivotal about either of said connecting means, said supporting means providing 35 means limiting movement of said draft member away from said buffer means, wedges respectively interposed between each of said heads and the respective end portions of said draft member, each of said wedges being longitudinally 40 split to form two parts and having yieldable means interposed between said parts, the side faces of each of said wedges frictionally engaging the friction faces of its associated head and the base portion of each of said wedges bearing 45 against an end portion of said draft member, plates respectively bridging the forward ends of the portions of each wedge, and yieldable means interposed between said plates and said heads respectively. 50
7. Car draft and buffer gearing comprising buffer means and a draft member, means supporting said buffer means and draft member for movements toward and away from each other, said buffer means comprising a pair of separate horizontally spaced hollow heads having forward buffing faces and said draft member having end portions extending behind said heads, said forward buffing faces projecting beyond said supporting means so as to take buff directly, each of 55 said heads having at its rear side integral portions providing a pair of forwardly convergent opposed friction faces, means connecting the side portions of said buffer means with said supporting means and limiting movement of said buffer means away from the draft member, said connecting means comprising abutment elements directly carried by said supporting means, said buffer means being pivotal about 60 said connecting means, said supporting means providing means limiting movement of said draft member away from said buffer means, means integral with said buffer means providing opposed forwardly convergent friction faces, means integral with said draft member providing convergent friction faces, wedge means interposed 65 between the friction faces of said buffer means and draft member respectively and having friction faces engaging the same, and means yieldingly urging the friction faces of said wedge means against said engaged faces. 70
8. Car draft and buffer gearing comprising buffer means and a draft member, means supporting said buffer means and draft member for movements toward and away from each other, said buffer means comprising a pair of separate horizontally spaced hollow heads having forward buffing faces and said draft member having end portions extending behind said heads, said forward buffing faces projecting beyond said supporting means so as to take buff directly, each of 75 said heads having at its rear side integral portions providing a pair of forwardly convergent opposed friction faces, means connecting the side portions of each of said heads with said supporting means and limiting movement of said heads away from the draft member, said connecting means comprising abutment elements directly carried by said supporting means, each of said heads being pivotal about either of said connecting means, said supporting means providing means limiting movement of said draft member away from said buffer means, wedges respectively interposed between each of said heads and the respective end portions of said draft member, each of said wedges having portions with friction faces engaging the friction faces of its associated head and the base portion of each of said wedges bearing against an end portion of said draft member, means yieldingly urging the wedge portions apart and yieldable means interposed between the leading ends of said wedges and their associated heads. 15

10. Car draft and buffer gearing comprising buffer means and a draft member, means supporting said buffer means and draft member for movements toward and away from each other 5
5 relative to said supporting means, said buffer means projecting forwardly beyond said supporting means so as to take buff directly, means connecting the side portions of said buffer means with said supporting means and limiting movement of said buffer means away from the draft member, said connecting means comprising abutment elements directly carried by said supporting means, said buffer means being pivotal about said connecting means, said supporting 10
10 means providing means limiting movement of said draft member away from said buffer means, means integral with said buffer means providing opposed forwardly convergent friction faces, means integral with said draft member providing 15
15 opposed rearwardly convergent friction faces opposite said first-named friction faces, a pair of wedges of which one has its sides frictionally engaged between each pair of said opposite friction faces, and means urging said wedges apart.
20 11. Apparatus according to claim 10 wherein the wedges are provided with aligned apertures, a bar is provided whose ends are in said wedge apertures, and the urging means is constituted by compression spring means encircling said bar 25
25 and bearing against said wedges.
30 12. Car draft and buffer gearing comprising buffer means and a draft member, means supporting said buffer means and draft member for movements toward and away from each other 30
30 relative to said supporting means, said buffer means projecting forwardly beyond said supporting means so as to take buff directly, means connecting the side portions of each of said buffer means with said supporting means and limiting movement of said buffer means away from the 35
35

draft member, said connecting means comprising abutting elements directly carried by the supporting means, said buffer means being pivotal about either of said connecting means, said supporting means providing means limiting movement of 5 said draft member away from said buffer means, said draft member having a portion extending behind said buffer means and carrying a forwardly faced wedge, a rearwardly faced wedge on said buffer means opposite the first-mentioned 10 wedge and spaced therefrom, a pair of opposed wedges engaging the faces of the first-mentioned wedges, and means urging said pair of wedges together whereby to normally maintain said buffering means and draft member in maximum spaced 15 relation.

13. Car draft and buffer gearing comprising buffer means and a draft member, means supporting said buffer means and draft member for movements toward and away from each other 20
20 relative to said supporting means, said supporting means comprising vertically spaced horizontally extending walls fixed to a car end and between which the buffer means is slidable, abutment means between said walls and engaging 25
25 the end portions of the buffer means to limit outward movement of the latter, the buffer means being pivotal about either of said abutment means, said draft member including a portion disposed behind the buffer means, means limiting movement of the draft member away from the buffer means, said buffer means having a forward portion projecting beyond said walls so as to take buff directly and having rear portions fixed thereto and providing convergently related friction faces, friction shoes engaging said friction faces, and spring means urging said shoes against said faces. 30
